(57) **CLAIM**

The ornamental design for a privacy booth, as shown and described.

DESCRIPTION

FIG. 1 is a front perspective view of a privacy booth according to a first embodiment of the new design;

FIG. 2 is a rear perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof;

FIG. 8 is a bottom view thereof;

FIG. 9 is a front perspective view thereof showing a door of the privacy booth in an alternate position;

FIG. 10 is a front view thereof showing the door in the alternate position of FIG. 9;

FIG. 11 is a front perspective view of a privacy booth according to a second embodiment of the new design;

FIG. 12 is a rear perspective view thereof;

FIG. 13 is a front view thereof;

FIG. 14 is a rear view thereof;

FIG. 15 is a right side view thereof;

FIG. 16 is a left side view thereof;

FIG. 17 is a top view thereof;

FIG. 18 is a bottom view thereof;

FIG. 19 is a front perspective view thereof showing a door of the privacy booth in an alternate position; and,

FIG. 20 is a front view thereof showing the door in the alternate position of FIG. 19.

The broken lines illustrate portions of the privacy booth that form no part of the claimed design.

1 Claim, 20 Drawing Sheets
